Patented June 4, 1918.

UNITED STATES PATENT OFFICE.

IVAR L. RUDOLPH, OF WASHINGTON, DISTRICT OF COLUMBIA.

UMBRELLA.

1,268,283.

Specification of Letters Patent. Patented June 4, 1918.

Application filed December 27, 1917. Serial No. 209,082.

To all whom it may concern:

Be it known that I, IVAR L. RUDOLPH, a citizen of Sweden, residing at Washington, in the District of Columbia, have invented 5 certain new and useful Improvements in Umbrellas, of which the following is a specification.

This invention relates to folding umbrellas.

10 The primary object of the invention is to provide an umbrella which is capable of being readily folded into small compass, so as to enable the same to be conveniently carried in a grip or a suit case. A further object of the invention is to provide an umbrella of this character which can also be folded in regular manner as readily and conveniently as a non-foldable umbrella. A still further object of the invention is to 15 provide a device of this character, which has its fabric supporting elements so assembled and arranged as to minimize the opportunity for breaking or unduly stretching the fabric, when the umbrella is raised, whereby the length of service of umbrellas of this character is greatly increased. Still further objects of the invention reside in providing a folding umbrella which shall be of simple and inexpensive construction, 20 which is composed of but few readily assembled parts, which is easy of operation, and which will prove thoroughly efficient in the attainment of the ends for which it is designed.

25 With these objects in view together with others which will appear as the description proceeds, the invention resides in the novel formation, combination and arrangements of parts, all as will be described more fully 30 hereinafter, illustrated in the drawings, and particularly pointed out in the claims.

In the drawings:

Figure 1, is a fragmentary sectional view taken through an umbrella embodying the 45 invention, the view illustrating the position the parts will assume when the umbrella is raised.

Fig. 2, is a view similar to Fig. 1 and illustrating the umbrella folded in regular 50 everyday-position.

Fig. 3, is a view showing the position of the parts when the umbrella is folded for packing into small space.

Referring to the drawings, 6 indicates 55 the umbrella staff, which in the present instance comprises an elongated tube open at

both ends. This tube may be formed of any suitable material and a tip 17 is detachably secured in one end thereof. This tip is of a diameter to fit snugly within the 60 staff 6 and has a shoulder 16 to limit the inward movement therein. The inner extremity of the tip has secured thereto a spring catch 15 for engagement within a notch or slot 14 in the staff 6. The handle 65 is indicated generally at 2 and comprises a stem-portion 29 to the outer end of which is secured a hand grip 1. The stem 29 is also of a size to fit snugly within the tubular staff 6, and carries a spring pressed 70 detent 3 adapted to engage within a notch or slot 7 in the staff 6. This detent locks the handle against inward or outward movement, but when moved to released position permits of the handle being readily slid inwardly or outwardly of the tubular staff. The inner end of the stem 29 is beveled or tapered as at 5 and when the same is moved inwardly of the staff this beveled end will engage the inclined outer extremity of the 80 spring catch 15 of the tip, so as to withdraw the detent 3 from engagement within the slot 14 in the staff. Further inward movement of the same will operate to eject the tip 17 from the staff, projecting outwardly 85 from the staff 6 adjacent the tip end thereof is the circular plate 18. This plate is preferably formed of metal and is bent downwardly and inwardly upon itself at its outer edge in such a manner as to form a 90 lip which extends and forms a lap over the fabric, which is fastened to a ring 21. This ring surrounds the plate in groove formed by plate, immediately under the lap. Plate 18 is then bent outwardly and downwardly 95 and inwardly and upwardly, forming a loop 19 at lower edge. Into this loop is cut notches to receive the ribs. The ribs comprise inner section 20 and outer section 27. The inner end of section 20 of the rib is 100 pivoted to loop 19 by a ring 30. The outer end of section 20 is pivoted to joint plate 25 which fits snugly in channel of rib. Outer section of rib 27 is fastened in similar manner to joint plate 25. Joint-plate 105 25 is so constructed as to fit snugly in channels of both rib sections and brace 13, and resting solidly in the bottom of said channels, so as to prevent rib-section 27 to swing inward, and to form a substantial frame 110 when umbrella is raised. On the upper and inner end of joint plate 25 is an extension

- onto which outer end of brace 13 is pivoted. Inner end of brace 13 is pivoted to a sliding sleeve 10 at 12. At the upper end of the sleeve the inside edge is beveled off 5 and thus the hole made a trifle larger in order to permit sleeve 10 to pass easily over lower end of staff 6 when raising the umbrella from position illustrated in Fig. 2. The spring catch 9 is positioned in the staff 10 6 so as to lock the sleeve 10 against sliding back when raised. Said catch 9 is flush on inside of staff 6 so as to permit handle 2 to slide through staff 6 when folding umbrella as in Fig. 3. When it is desired to fold the 15 umbrella as shown in Fig. 2, the spring catch 9 is forced inwardly and the sleeve 10 is moved toward handle. This action moves the fabric supporting ribs inwardly to closed position.
- 20 When it is desired to fold the umbrella as shown in Fig. 3 the spring catch 9 is forced inwardly, and the sleeve 10 is moved toward the handle until tension on fabric has ceased, then the outer section 27 of the 25 rib is swung outward and toward tip 17 describing a circle with pivot 26 as center. When rib section 27 has assumed a square position to joint plate 25, said joint plate will move with rib section 27 swinging on pivot 24. When both rib sections have been 30 folded together, with the fabric doubled between them, sleeve 10 is pushed toward the tip 17 until ribs 13 rest against staff 6. Spring catch 3 is then forced inwardly 35 and section 2 of handle is pushed through staff 6. Beveled end of handle 2 engages spring catch 15 on tip 17 releasing same from notch 14 in staff 6. Further pressure on handle 2 will eject tip 17.

Copies of this patent may be obtained for five cents each, by addressing the "Commissioner of Patents, Washington, D. C."

While the present disclosure is the embodiment of the invention, it is to be understood that various changes in the minor details of construction, proportion and arrangements of parts may be made without departing from the spirit of the invention as defined in the appended claims.

What I claim is:

1. In a folding umbrella a hollow upper staff section a detachable tip means for locking the tip to the staff a lower staff section, 50 said lower section adapted in collapsing within the upper section to disengage said tip locking means.
2. The device defined in claim 1 and the 55 lower section is adapted to eject the tip from the upper section.
3. In a folding umbrella an upper hollow staff section a tip detachably engaged within said section a catch on the tip to engage 60 said section a lower staff section slidably engaged within the upper section the upper end of the lower section being formed to disengage the catch and eject the tip when the lower section is collapsed within the upper section.
4. In a folding umbrella a rib comprising inner and outer sections, each U shaped in cross-section a joint-plate pivoted within the sides of the rib sections and a brace pivotally connected to the joint-plate.

In testimony whereof I affix my signature in presence of two witnesses.

IVAR L. RUDOLPH.
